(57) **CLAIM**

The ornamental design for a vaporizer with indicators, as shown and described.

DESCRIPTION

FIG. 1 is a front perspective view of a vaporizer with indicators;

FIG. 2 is a front view of the vaporizer with indicators of FIG. 1;

FIG. 3 is a side view of the vaporizer with indicators of FIG. 1;

FIG. 4 is a bottom view of the vaporizer with indicators of FIG. 1; and,

FIG. 5 is a top view of the vaporizer with indicators of FIG. 1.

The broken lines in the drawings depict parts of the vaporizer with indicators that form no part of the claimed design.
